UNITED STATES PATENT OFFICE.

HORACE E. RICE AND ROBERT C. DA COSTA, OF PHILADELPHIA, PENNSYLVANIA; SAID DA COSTA ASSIGNOR TO ATWATER KENT MANUFACTURING COMPANY, OF PHILADELPHIA, PENNSYLVANIA, A CORPORATION OF PENNSYLVANIA; KATHLEEN F. RICE ADMINISTRATRIX OF SAID HORACE E. RICE, DECEASED.

CONDENSER STRUCTURE.

Application filed March 18, 1921. Serial No. 452,888.

Our invention relates to condenser structures, as separate condenser units and the method of making the same; and our invention relates further to the combination with 5 an induction coil structure of a condenser structure or unit, particularly when the induction coil and condenser are utilizable for the electric ignition of combustible charges in internal combustion engines.

10 Our invention resides in the method and features of structure and combination hereinafter described and claimed.

For an understanding of our invention, reference is to be had to the accompanying 15 drawings, illustrating some of the various forms our invention may take, and in which Fig. 1 is a plan view of condenser elements before rolling.

Fig. 2 is a plan view of a condenser after 20 rolling.

Fig. 3 is a fragmentary plan view of a modified form of condenser.

Fig. 4 is a fragmentary sectional view of 25 the same condenser.

Fig. 5 is partially a diagram and partially an elevational view of induction coil and condenser structures in an ignition system.

Fig. 6 is an elevational view of an induction coil and condenser unit mounted thereon.

30 Fig. 7 is a view at right angles to Fig. 6, partly in vertical section.

Fig. 8 is a horizontal sectional view taken on the line 8—8 of Fig. 6.

Fig. 9 is a fragmentary perspective view, 35 partially in section, of an element of the condenser unit.

In accordance with our invention, a condenser unit is formed by housing in a closed container a condenser of any suitable form 40 or type. For ignition purposes, however, we prefer a so-called rolled condenser comprising ribbons of tin foil separated by paper rolled to form a reasonably compact structure.

45 In Fig. 1 are shown the ribbons or strips of metal or tin foil *a* and *b*, separated by paper or other sheet insulating material *c*.

To form electrical connection with the armature or foil strip *a*, a plurality of thin easily 50 flexed metal connectors or strips *d*, as of copper, lie against the armature *a* at suitably numerous points along its length, and extend

outwardly at right angles thereto beyond the edge of the paper or dielectric *c*. Similar connectors *e* lie against the other foil strip or 55 armature *b*. When the armatures and dielectric are rolled up to form a condenser *C*, as indicated in Fig. 2, the connectors *d* preferably come adjacent to each other, though preferably staggered as indicated. And the 60 connectors *e* are also preferably similarly disposed.

While the foregoing is our preferred form of rolled condenser, the form indicated in 65 Figs. 3 and 4 may be employed. In this instance the sheet of paper or strip of dielectric *c* lies between the foil strips or armatures *a* and *b*, but the armature *a* extends beyond the margin of the dielectric *c* on one side, while the armature or strip *b* extends beyond the 70 other edge of the paper or dielectric *c*. When the foil strips and dielectric sheets are rolled up, as to form similar to that indicated in Fig. 2, the edges of the armatures *a* and *b* will be 75 exposed on opposite sides of the roll, as indicated in Fig. 4, and the different turns or convolutions of each armature may be brought together and compressed, or soldered, so that in lieu of condenser terminals *d* and *e* as in Figs. 1 and 2, the entire extent of each 80 armature will be directly connected to the terminal formed of the compressed edges of the armature.

Referring now to Figs. 5 to 9 inclusive, *K* is 85 a housing member in the form of a receptacle into which the condenser *C*, whether of rolled type or other type, is placed, as indicated in Figs. 7 and 8. When placed in position in the housing *K*, the connectors of one set, as *e*, 90 communicating with one armature of the condenser *C*, are electrically connected to the metallic plate *f*, as by soldering or otherwise. In case the condenser be of the type indicated in Figs. 3 and 4, the compressed or united edges of one of the condenser armatures, as 95 *b*, will be connected to the plate *f*. The plate *f* is secured by one or more rivets *g* to an inner wall at one end of the metal housing or casing *K*, a strip *h* of insulating material intervening between the plate *f* and the metal 100 wall of the housing *K*, this insulating material also preferably extending, as indicated in Fig. 7, in contact with the inner wall of the housing *K* and terminating between the

condenser C and the outer wall of the housing; and the other end of the insulating strip *h* extending over the opposite side of the condenser C. The rivets *g* extend through holes 5 in the outer wall of the housing K, in which holes may be provided insulating bushings *i*. Under the heads or outer ends of the rivets *g* is confined the metal terminal *j*, between which and the housing K intervenes the insulating material *k*.

The connectors of the other set, as *d*, are bent into position to contact with the housing K, to which they may be soldered; or as indicated in Fig. 7; the free ends of the connectors *d* may extend to position to contact with the closing cover or plate *m*, of sheet metal, as tinned iron or the like, having the side and end flanges *n* fitting into the housing K. Or if the condenser be of the type indicated in Figs. 3 and 4, the united edges of the other armature *a* may be connected to or contact with the housing K or the cover plate *m*.

With the parts thus in the position described, great pressure, as of the order of a 25 ton, is applied to the cover or plate *m*, thereby compressing the condenser roll C. While so held compressed, the plate *m* is soldered, welded or otherwise secured to the housing K. As indicated in Figs. 7 and 8, this attachment is effected by solder *o*, which effects a pressure-tight joint between the housing K and the plate *m*. After soldering or otherwise securing the plate *m* to the housing K, the pressure upon the plate *m* is removed, the 35 condenser C, however, being held compressed, and for this purpose the arched or arcuate shape of the plate *m*, as indicated in Figs. 8 and 9, is of advantage in resisting the outward force exerted on its convex surface by 40 the condenser C.

With the condenser so held compressed within the housing, the unit is subjected to impregnation, by placing in a bath of molten insulating wax or equivalent in a vacuum, the 45 air being removed by air pump from within the housing K through the hole *p*. When the air has been removed to sufficient degree, atmospheric or other pressure is exerted upon the bath, causing the wax to rush in through 50 the hole *p* and impregnate the condenser C itself and also fill the spaces around the same with molten wax, indicated at *q*. With the wax still molten within the housing K, that is, while the temperature of the housing and 55 its contents are still elevated, the hole *p* is sealed air-tight, as by soldering. Upon cooling the wax solidifies and to some extent contracts, with the result that with the housing sealed as described, there is at ordinary temperatures a slight vacuum within the housing K.

A condenser unit so constructed accordingly has one terminal of the condenser at *j*, and the other terminal is the housing K itself, and 60 accordingly connection to the other terminal

or armature of the condenser may be effected, as by binding screw *r* threaded into the housing K itself.

In Figs. 5 to 8 inclusive, H is a housing, as of sheet metal, for an induction coil comprising, as usual, a magnetic core structure and primary and secondary windings. The primary winding is indicated at P, Fig. 5, and the high tension secondary at S. In the example illustrated, one terminal of the primary P connects with the binding post *s* carried by the cap A, of molded insulating material, forming a closure for one end of the casing H. The other terminal of the primary P and one terminal of the secondary S are 70 connected to the binding post *t*, carried by the cap A; and the other end of the secondary S connects to the terminal socket *u*, in the cap A. 75

As shown in Figs. 6 and 7, the condenser unit terminal *j* connects with one of the primary binding posts, as *s*. The condenser unit itself is mounted upon the induction coil casing or housing H, and is held thereto by the spring strap *v* embracing the casing H and having spring hook ends *w* engaging in recesses in the bosses *x*, on opposite side walls of the housing K. Where the housing or casing H is cylindrical as indicated, the radius of curvature of the plate *m* may correspond more or less closely with the curvature of the housing H to fit the same, as indicated in 80 Fig. 8.

And in general, whatever the form or shape of the induction coil structure upon which the condenser unit is mounted, the condenser unit may be formed to conform to its supporting induction coil or housing where they engage or contact with each other. 85

As indicated in Fig. 5, the primary terminal *t* may connect through the ignition switch 103 *y* with one terminal of the battery B, whose other terminal is grounded or connected to the mass or frame of the internal combustion or other apparatus at G. The binding post *s* may connect with one contact, as *z*, of an 110 interrupter whose movable contact, as *a*¹, is controlled or actuated by the engine driven cam *b*¹, the contact *a*¹ being connected to ground G. By the structure shown, one terminal of the condenser, through the terminal *j* and binding post *s*, is connected with one contact of the interrupter structure, while by conductor *c*¹ the other terminal of the condenser is connected to the other contact of the interrupter. Accordingly, the 115 condenser is as usual shunted across the interrupter, reducing the sparking thereat and increasing the operating characteristic of the high tension secondary S. As usual, the secondary S, as by flexible conductor *d*¹, connects with a rotor or distributor *e*¹, rotating in synchronism with the cam *b*¹, and co-acting with stationary distributor contacts *f*¹, with each of which is connected a spark plug *g*¹, the spark plugs being disposed in different 120 125 130

cylinders of the engine, as well understood in the art.

It will be understood that where the casing H is of metal, and its metal base h¹ is connected to the metallic mass or frame of the apparatus, that is, when the casing H is of metal and is grounded, the conductor c¹ may be omitted if the housing K makes electrical contact with the housing or casing H. And it will be understood that where the contact a¹ is permanently grounded to the framework of the engine, as indicated, the conductor c¹ may be connected to the same engine framework or grounded.

15 While we have herein shown the induction coil as enclosed in a housing, it will be understood that our invention comprehends the mounting of a condenser unit upon an induction coil structure of any character; and it 20 will be further understood that our condenser unit may be utilized in other relations or for any other purpose.

What we claim is:

1. The method of producing a condenser unit, which consists in placing a condenser within a housing, closing the housing with a closure member, transmitting pressure through said closure member to said condenser to compress the same, securing the closure member to the housing while said condenser is held compressed by said closure member, and thereafter removing air from said housing and introducing molten insulating material.

35 2. The method of producing a condenser unit, which consists in placing a condenser within a housing, closing the housing with a closure member, transmitting pressure through said closure member to said condenser to compress the same, securing the closure member to the housing while said condenser is held compressed by said closure member, thereafter removing air from said housing and introducing molten insulating material, and thereafter sealing said housing.

45 3. The method of producing a condenser unit, which consists in placing a condenser within a housing, closing the housing with a closure member, transmitting pressure through said closure member to said condenser to compress the same, securing the closure member to the housing while said condenser is held compressed by said closure member, thereafter removing air from said housing and introducing molten insulating material, and thereafter sealing said housing while at elevated temperature.

55 4. The method of producing a condenser unit consisting of a condenser and an enclosing housing therefor, which comprises placing within a housing an unimpregnated condenser structure, closing the housing with a closure member, transmitting pressure through said closure member to said condenser to compress the same, and thereafter

removing air from said housing and introducing impregnating material into said housing and into said condenser structure while held compressed.

5. The method of producing a condenser unit, which comprises placing a condenser within a housing, closing the housing with a closure member, transmitting pressure through said closure member to the condenser to compress the same, securing the closure member to the housing while said condenser is held compressed by said closure member, and thereafter introducing into said housing into the space therein surrounding said condenser heated fluid insulating material which congeals upon cooling.

6. The method of producing a condenser unit, which consists in placing a condenser within a housing, applying a closure member to the housing, thereafter introducing the closed housing with contained condenser into a bath of molten insulating material under sub-atmospheric pressure for removal of air from said housing through an aperture therein, and thereafter increasing the pressure upon said bath to cause introduction of said insulating material into said housing.

7. The method of producing a condenser unit, which consists in placing a condenser within a housing, applying a closure member to the housing, thereafter introducing the closed housing with contained condenser into a bath of molten insulating material under sub-atmospheric pressure for removal of air from said housing through an aperture therein, thereafter increasing the pressure upon said bath to cause introduction of said insulating material into said housing, and thereafter sealing said aperture.

8. A condenser unit comprising a housing, a condenser therein, and an arcuate closure member exerting pressure on said condenser and having marginal flanges extending into and lying along the walls of said housing.

9. A rolled condenser comprising a plurality of strips of conducting material and intervening dielectric, and a plurality of conducting connectors spaced from each other longitudinally of one of said conducting strips disposed between said conducting strip and a dielectric strip of the condenser roll and projecting beyond an end of the roll.

10. A rolled condenser comprising a plurality of conducting strips and intervening dielectric, a plurality of conducting connectors spaced from each other longitudinally of one of said conducting strips in contact therewith and projecting beyond an end of the roll, the spacing of said connectors longitudinally of said conducting strip being such that said connectors lie adjacent each other upon completion of the roll.

11. A condenser unit comprising a metallic housing, a condenser therein, terminal conductors extending beyond the opposite

105

110

115

120

125

130

edges of said condenser, a closure plate secured and sealed to said housing thereby clamping terminal conductors at one end of said condenser between said condenser and 5 said plate, and enclosing and holding said condenser compressed, and an integral mass of insulating material of uniform composition impregnating said condenser therewith and also filling the spaces between said condenser and the housing walls.

10 12. A condenser unit comprising a conducting housing, a terminal connector electrically connected to said housing, a rolled condenser therein, conducting terminals extending beyond the opposite ends of said condenser, a closure member secured to said housing and in close engagement with said

condenser thereby effecting electrical connection between one of said terminals and said housing, an insulating strip located between 20 the opposite end of said condenser and the conducting housing thereby insulating the corresponding terminal from the housing, a terminal connector insulated from the housing and connected with said terminal, and an integral mass of insulating material extending into said condenser and filling the space 25 around said condenser within said housing.

20 25 In testimony whereof we have hereunto affixed our signatures this 14th day of March, 1921.

HORACE E. RICE.
ROBERT C. DA COSTA.
